Switzerland

CLAIM

The ornamental design for a handle for covers of cooking utensils, as shown and described.

DESCRIPTION

FIG. 1 is a top front perspective view of a handle for covers of cooking utensils showing my new design, the broken line showing of a cover being for illustrative purposes only;

FIG. 2 is a front elevational view thereof, the rear elevational view is a mirror image thereof;

FIG. 3 is a top plan view thereof;

FIG. 4 is a bottom plan view thereof;

FIG. 5 is left end elevational view thereof;

FIG. 6 is a right end elevational view thereof.
